CLAIM

The ornamental design for a guitar neck as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a perspective view of the guitar neck showing our new design in its fully extended position;

FIG. 2 is a top plan view of the guitar neck shown in FIG. 1;

FIG. 3 is a bottom plan view of the guitar neck shown in FIG. 1;

FIG. 4 is a right side elevational view of the guitar neck shown in FIG. 1;

FIG. 5 is a left side elevational view of the guitar neck shown in FIG. 1;

FIG. 6 is a front elevational view of the guitar neck shown in FIG. 1; and,

FIG. 7 is a back elevational view of the guitar neck shown in FIG. 1.

The broken lines represent the portions of the guitar neck that form no part of the claim.

1 Claim, 7 Drawing Sheets
